HARRY A. DAVIS, OF HOPEDALE, MASSACHUSETTS, ASSIGNOR TO DRAPER CORPORATION, OF HOPEDALE, MASSACHUSETTS, A CORPORATION OF MAINE

LOOM

Application filed August 6, 1929. Serial No. 383,846.

This invention relates to looms and more especially to looms wherein the operative condition of the loom is changed from time to time, and is directed to shuttle feeler control mechanism.

It is now the ordinary practice to provide looms and especially those of the filling replenishing type, with a shuttle feeler for determining whether or not the shuttle is properly boxed preceding filling replenishment. In such looms it has been the practice heretofore to move the shuttle feeler to shuttle feeling position by a transverse or rock shaft when such shaft is actuated by a filling detecting mechanism and indicates a fault in the filling. The filling detecting mechanism has usually comprised a filling feeler which on detection of substantial exhaustion of filling causes the rock shaft to be actuated through a train of mechanism under feeler control, and upon such actuation of the transverse or rock shaft the shuttle feeler which has been directly connected to the rock shaft is moved to its shuttle feeling position and frequently reaches such position before the shuttle has completed its picking movement, with the result that the shuttle feeler frequently strikes the shuttle during its picking movement with injurious effect to the shuttle and probable breakage of parts.

Since the purpose of the shuttle feeler is to determine whether the shuttle has been properly boxed for the transfer of a filling carrier to the shuttle, this premature movement of the shuttle feeler is unnecessary, and one of the purposes of the present invention is to provide means for moving the shuttle feeler to its shuttle feeling position subsequent to a detection of filling fault after an interval of time sufficient to permit the shuttle to complete its picking movement, so that when the shuttle feeler is moved to its shuttle feeling position, it is prevented from engagement with the shuttle during its picking movement.

In accordance with the present invention, the shuttle feeler is moved to its shuttle feeling position by a train of mechanism operating independently of the transverse or rock shaft, and consequently the movement of the shuttle feeler to its shuttle feeling posi-

tion may be delayed until after the shuttle has completed its picking movement, so that all danger of injury to the shuttle is avoided.

The invention and novel features thereof will best be made clear from the following description and the accompanying drawings of one good form or embodiment thereof.

In the drawings:

Fig. 1 is a perspective view of portions of a loom containing the present invention;

Fig. 2 is an enlarged perspective detail showing the means for locking the shuttle feeler to its operating means upon rotative movement of the transverse or rock shaft;

Fig. 2^a is an enlarged detail, partly in section, showing a portion of the operating arm of the feeler control mechanism provided with a slot or opening by which it may be locked to the feeler;

Fig. 3 is a side elevation, with parts in section, showing portions of a loom with the present invention associated therewith;

Fig. 4 is a sectional detail showing the means for locking the shuttle feeler to its control mechanism.

The loom frame 1 and lay 2 may be of usual construction, and mounted in suitable bearings 3 on the loom frame is the transverse or rock shaft 4 to which is secured an arm 5 extending upwardly therefrom and having pivotally connected thereto an actuator 6, the rear end portion 7 of which is adapted to be engaged by an operating member 8 when the filling feeler detects substantial exhaustion of filling in the shuttle. The operating member 8 may be constituted as the usual cam follower or a part connected therewith and is pivoted at 9, from which extends the arm 10 having a shoe 11 which rides upon the usual cam 12 on the under or cam shaft 13.

As hereinbefore noted, the rocking movement of the rock shaft is under control of a filling detector which in the present instance of the invention is typified as a feeler 14 mounted upon the feeler stand 15 for movement towards and from the front of the loom and in a direction longitudinally of the shuttle, as more fully and completely explained in the Edward S. Stimpson Patent, No.

1,309,226, dated July 9, 1919. The feeler mechanism, however, may be of any usual type now well-known and further explanation of the particular mechanism shown in the drawings will be unnecessary as it is described in the Stimpson patent to which reference may be had. The construction is such, however, that when the feeler 14 side slips, or indicates substantial exhaustion of filling in the shuttle, it will cause rocking movement of the rock shaft 4 as described in the Stimpson patent.

The lay 2 has the usual shuttle boxes 16, one at each end of the lay, and on the detecting side of the loom the front wall of the shuttle box is provided with an opening 17 through which the feeler may pass on detecting beats to feel for the filling in the shuttle. The parts so far described may be of any or usual construction.

The shuttle feeler 18 is pivotally mounted at 19 on a bracket 20 secured to the loom frame, and extending laterally from the feeler is a pin or similar device 21 by which the dog 22 of the replenishing mechanism may be moved to and from its operative position, as usual. The dog 22 is pivotally connected to an arm 23 extending downwardly from the hub 24 of the transfeerer 25, and when the dog 22 is lifted into dotted line position, Fig. 3, it may be engaged by a bunter 26 mounted on the lay to effect transfer of a filling carrier supplied with filling to the shuttle.

The shuttle feeler may if desired be provided with a filling parter to part or cut the filling thread leading from the depleted filling carrier or bobbin in the shuttle, and one form of such parter is shown, but as it forms no special part of the present invention and may or may not be employed, and is also well-known in the art, further description thereof appears unnecessary.

The shuttle feeler controlling mechanism for moving the shuttle feeler to its shuttle feeling position at a time subsequent to the rocking movement of the rock shaft may be variously contrived but as herein shown it comprises an operating arm 27 which is loosely mounted on the transverse or rock shaft 4 and its rearwardly extending end portion is provided with a shoe 28 which engages a cam 29, as indicated in Figs. 1 and 3. The cam 29 is shown as mounted on the under or cam shaft 13 as a convenient means for actuating the operating arm, the result being that during the loom operation the arm 27 will be continuously actuated, and the present invention contemplates that the shuttle feeler be connected with the operating arm in order to move the shuttle feeler into its rearward feeling position following an indication of filling fault by the feeler.

Loosely mounted upon the transverse or rock shaft 4 is a shuttle feeler member 30 which depends downwardly from the rock

shaft 4, as shown, and its lower arm 31 extends rearwardly into engagement with a projection or pin 32 extending from the feeler 18. In order that the connection between the feeler and rearwardly extending arm 31 may be yielding to a degree, the arm 31 has hung thereon a jaw member 33 which is normally under the influence of a spring 34 to hold the jaw 35 of the jaw member in engagement with the projection or pin 32 extending from the feeler, the construction being such that should the arm 31 be moved upwardly, in the present instance of the invention, the shuttle feeler will be moved to its shuttle feeling position.

As above noted, the member 31 thus connected to the shuttle feeler is loosely mounted upon the transverse or rock shaft 4 and is consequently inactive to effect any movement of the shuttle feeler to shuttle feeling position by the operating arm 27 during normal weaving operations, so that while the operating arm 27 is continuously in operation during weaving, the shuttle feeler will remain in its frontward or non-shuttle feeling position. When, however, the filling feeler has indicated substantial exhaustion of filling in the shuttle and the rock shaft 4 is consequently actuated, the present invention provides that the shuttle feeler member shall be connected for operative movement to the operating arm 27 and consequently move the shuttle feeler to its shuttle feeling position after a lapse of time sufficient to permit the shuttle to complete its picking movement.

The means to this end may be variously contrived, but as shown in the present instance of the invention it consists of a lock or connecting device whereby on rocking movement of the rock shaft the shuttle feeler member will be operatively connected to the operating arm 27 and consequently moved to its shuttle feeling position.

The operating arm 27, in the present instance, is provided with a slot or opening 36, as indicated in Figs. 1 and 2^a, which is adapted to be engaged by a locking device carried by the shuttle feeler member to thereby connect the operating arm 27 to the shuttle feeler.

As shown more clearly in Figs. 2 and 4, the downwardly extending portion 30 of the shuttle feeler member is bifurcated, as indicated at 37, and mounted in the bifurcation 37 is a lock 38 pivotally mounted at 39 and having its upper portion 40 extending laterally therefrom.

Mounted on the transverse or rock shaft 4 is a lock actuator 41 which is secured to the rock shaft for rotative movement therewith by suitable means, such, for instance, as the bolt 42, Figs. 2 and 4. The lower edge portion of the lock actuator 41 normally rests upon the lateral extension 40 of the lock, which in normal position is shown by full

lines in Fig. 4, the construction being such that upon rotative movement of the transverse or rock shaft 4 the lock actuator 41 will be turned as indicated in Fig. 2 to cause the lower edge portion 43 thereof to ride upon the lateral projection 40 of the lock and swing it about its pivotal mounting into engagement with the slot 36 of the operating arm 27, thereby operatively connecting the shuttle feeler with the operating arm.

Since the lock is actuated or moved into locking position with relation to the operating arm by rotative movement of the transverse or rock shaft 4, the operative engagement of the lock with the operating arm is effected after the lapse of sufficient time to permit the shuttle to complete its picking movement, so that the shuttle feeler is moved into shuttle feeling position when the shuttle has come to rest, thereby obviating any danger of injurious contact of the shuttle feeler with the shuttle during its picking movement.

Since the shuttle feeler member 31 has its portion 30 loosely mounted on the transverse or rock shaft 4 it can no longer act under the impulse of the spring 34 as usual to return the rock shaft to its normal position after an indication of filling exhaustion, and to effect this desired operation the lock actuator 41 has its toe portion 44 extended rearwardly, and interposed between the loom frame or breast beam 45 and the toe of the actuator is a spring 46 which, on backward movement of the cam follower, turns the rock shaft 4 to its normal position.

The loosely mounted operating arm 27 and the loosely mounted shuttle feeler member 31 are shown in the present instance of the invention as maintained in their associated relation between a collar 47, secured to the transverse or rock shaft 4 by means such for instance as the bolt 48, and the operating member 41.

Referring to Fig. 1 it will be noted that the cam 12 for operating the cam follower or weft hammer and the cam 29 for actuating the operating arm 27 are disposed at angular relation, such that the cam follower will effect rotative movement of the transverse or rock shaft 4 before the operating arm 27 moves in a direction to actuate the shuttle feeler, with the result that there is a delay or lapse of time sufficient to permit the shuttle to complete its picking movement before the shuttle feeler is moved rearwardly into its shuttle feeling position, thereby obviating all danger of contact of the shuttle feeler with the shuttle during its picking movement.

The described mechanism presents a good practical form of the invention but obviously the train of mechanism for operating the shuttle feeler and moving it to its shuttle feeling position only after the shuttle has completed its picking movements may be

variously modified without departing from the true scope of the present invention.

It will be noted that the cam 29 and the operating arm or lever 27 act direct to move the shuttle feeler to shuttle feeling position independent of the rockshaft, thus remedying the objections heretofore experienced due to springing of parts at the left side of the loom and torsional give of the rockshaft. Also should the shuttle feeler detect an improperly boxed shuttle by the ordinary construction now commonly employed, the shuttle feeler spring comes into play by the forward movement of the shuttle feeler as the lay beats up, with the result that this strain is transmitted through the rock-shaft to the parts at the opposite side of the loom causing the parts to become loose and often requiring a complete resetting of the whole train of mechanism. With the present invention, however, no strain whatever is transmitted to the parts at the filling feeler side of the loom since the shuttle feeler is moved to its shuttle feeling position by means operating independent of the rock-shaft movement.

What is claimed is:

1. In a loom, the combination of a filling detector for indicating a fault in the filling conditions, a shuttle feeler to feel for the shuttle and determine if it is properly boxed, means connected to the shuttle feeler for moving it to feeling position, an actuator for said means normally disconnected therefrom, and devices for connecting said means to its actuator on detection of a filling fault that the shuttle feeler may be moved to its feeling position by the actuator and be prevented from engagement with the shuttle during its picking movement.

2. In a loom, the combination of a filling detector for indicating a fault in the filling condition, a shuttle feeler to feel for the shuttle following an indication of a filling fault and determine if it is properly boxed, means connected to the shuttle feeler for moving it to and from feeling position, a continuously operating actuator for said means normally disconnected therefrom, and locking devices rendered effective on detection of a filling fault for locking said means to the continuously operating actuator that the shuttle feeler may be moved to feeling position by the actuator.

3. In a loom, the combination of a feeler to detect the condition of the filling in the shuttle, a shuttle feeler at the opposite side of the loom to feel for the shuttle and determine if it is properly boxed, means connected to the shuttle feeler for moving it to feeling position, an actuator for said means normally disconnected therefrom, a cam for operating the actuator, and a locking device rendered effective on detection of a filling fault to lock the said means and its actuator

together that the shuttle feeler may then be moved to shuttle feeling position.

4. In a loom, the combination of a filling detector for indicating a filling fault, a shaft

5 actuated on the occurrence of a fault in the filling, a shuttle feeler actuating means for moving the shuttle feeler to shuttle feeling position, and a lock for connecting the shuttle feeler to its actuating means on the occurrence

10 of a fault in the filling that the shuttle feeler may thereafter be moved to shuttle feeling position by its actuating means and prevented from engagement with the shuttle during its picking movement.

15 5. In a loom, the combination of a filling feeler to feel for the filling in the shuttle, a rock shaft which is actuated when the feeler detects depletion of the filling in the shuttle to a predetermined extent, a shuttle feeler

20 to feel for the shuttle and determine if it is properly boxed, means normally disconnected from the feeler and operating independent of the rock shaft movement for moving the shuttle feeler to shuttle feeling position, and

25 a lock rendered effective by rock shaft movement for connecting the shuttle feeler to its operating means.

6. In a loom, the combination of a filling feeler to feel for the filling in the shuttle on

30 detecting beats, a rock shaft extending transversely of the loom, means for rocking the rock shaft rendered operative upon detection of substantial exhaustion of the filling in the shuttle, a shuttle feeler at the side of the

35 loom opposite the filling feeler, means continuously operating to effect movement of the shuttle feeler to shuttle feeling position, and means for connecting the shuttle feeler with its operating means only when the rock shaft is rocked on detection of substantial exhaustion

40 of filling in the shuttle by the filling feeler.

7. In a loom, the combination of a filling feeler, a rock shaft, means for rocking the

45 rock shaft on detection of approaching exhaustion of filling, a shuttle feeler, means operating independent of rock shaft movement for moving the shuttle feeler to shuttle feeling position, and means rendered effective by rock shaft movement for connecting the shuttle feeler to its operating means.

8. In a loom, the combination of a filling feeler, a rock shaft, means for rocking the

50 rock shaft on detection of approaching exhaustion of filling, a shuttle feeler, means operating independent of rock shaft movement for moving the shuttle feeler to shuttle feeling position subsequent to the rock shaft movement, and means rendered effective by

55 rock shaft movement for connecting the shuttle feeler to its operating means.

9. In a loom, the combination of a filling feeler, a transverse rock shaft and operating

60 means therefor controlled by the filling feeler, a shuttle feeler, an arm loosely mount-

ed relative to the rock shaft, means for operating the arm to move the shuttle feeler to shuttle feeling position after the shuttle has completed its picking movement that the shuttle feeler may not engage the shuttle during its picking movement, and means rendered effective by the rock shaft movement for connecting the shuttle feeler to the said arm.

10. In a loom, the combination of a filling

75 feeler, a rock shaft controlled in its rocking movement by the filling feeler, a shuttle

feeler, means operating independent of rock

shaft movement for moving the shuttle feeler

80 to shuttle feeling position, comprising an

arm loosely mounted on the rock shaft, means

85 for moving said arm in a direction to move

the shuttle feeler to feeling position subse-

90 quent to the rock shaft movement to enable

the shuttle to complete its picking move-

95 ment before the shuttle feeler reaches shuttle

feeling position, and means rendered effec-

100 tive by the rock shaft movement to connect

the shuttle feeler to the said arm.

11. In a loom of the character described,

105 the combination of a filling feeler, a rock

shaft controlled in its rocking movement by

110 the filling feeler, a shuttle feeler, means

115 loosely connecting the shuttle feeler with the

rock shaft, an operating arm loosely mount-

120 ed on the rock shaft and normally discon-

125 nected from the shuttle feeler, and a lock

130 actuated by rock shaft movement to lock the

135 shuttle feeler to said operating arm.

12. In a filling replenishing loom, the com-

140 bination of filling replenishing mechanism,

145 a filling feeler, a rock shaft extending trans-

150 versely of the loom, means under control of

155 the filling feeler for rocking said shaft, a

160 shuttle feeler, a member connected to the

lock actuated by rock shaft movement for locking the said member to the operating arm, and means for rendering the replenishing mechanism operative through shuttle 5 feeler movement.

14. In a filling replenishing loom, the combination of replenishing mechanism, a filling feeler, a transverse rock shaft, means under control of the feeler for rocking the shaft, a shuttle feeler, a member loosely mounted on the rock shaft and connected to the feeler, an operating arm loosely mounted on the rock shaft for moving the shuttle feeler to shuttle feeling position, a cam for operating the 10 arm, a locking device between said member and arm normally out of locking position, and means carried by the transverse rock shaft for throwing the locking device into locking position to connect the member and 15 arm upon rocking movement of the rock shaft.

In testimony whereof, I have signed my name to this specification.

HARRY A. DAVIS.
